UNITED STATES PATENT OFFICE.

AARON M. WEBER, OF OSHKOSH, WISCONSIN.

DESIGN FOR SKIRT FACING AND BINDING.

SPECIFICATION forming part of Design No. 31,424, dated August 15, 1899.

Application filed April 14, 1899. Serial No. 713,061. Term of patent 7 years.

To all whom it may concern:

Be it known that I, AARON M. WEBER, a citizen of the United States, residing at Oshkosh, in the county of Winnebago, State of Wisconsin, have invented a certain new and original Design for a Skirt Facing and Binding, of which the following is a description, reference being had to the accompanying drawings, and to the letters of reference marked $\circ$ thereon.

My invention relates to a new and original design for a facing and binding for garments; and the leading feature consists in a facing and binding of the shape and configuration $\circ$ hereinafter described, and shown in the accompanying drawings, in which—

Figure 1 is a front view showing my facing and binding, and Fig. 2 is a cross-section of the same.

In the drawings, B represents the folded $\circ$ facing, and C is a brush the lower end of which extends below the fold of the facing. The appearance of the binding is clearly indicated in Fig. 1.

Having thus described my invention, what $\circ$ I claim, and desire to secure by Letters Patent, is—

The design for a skirt facing and binding; substantially as shown and described.

In testimony whereof I affix my signature $\circ$ in presence of two witnesses.

AARON M. WEBER.
